UNITED STATES PATENT OFFICE.

PAUL KESTNER, OF LILLE, FRANCE, ASSIGNOR TO KESTNER EVAPORATOR COMPANY,
OF PHILADELPHIA, PENNSYLVANIA, A CORPORATION OF PENNSYLVANIA.

APPARATUS FOR CONCENTRATING LIQUIDS.

1,013,091.

Specification of Letters Patent. Patented Dec. 26, 1911.

Original application filed November 1, 1909. Serial No. 525,710. Divided and this application filed July 20, 1910. Serial No. 572,855.

To all whom it may concern:

Be it known that I, PAUL KESTNER, a citizen of the Republic of France, and a resident of Lille, Department Nord, France, have invented certain Improvements in Apparatus for Concentrating Liquids, (being a division of my application filed November 1, 1909, Serial No. 525,710,) of which the following is a specification.

10 My invention relates to apparatus for evaporating liquid or liquid bodies; and the object of my invention is to provide improved means for feeding such liquid or liquid bodies to the base of vertical tube evaporators in which concentration or evaporation is effected by the climbing of the liquid within elongated tubes externally heated that will insure an even and simultaneous feed of the liquid or liquid bodies 20 thereto.

In modern types of evaporators, the liquid to be evaporated is usually conducted as a film or layer traveling over or through heated tubes, as the case may be. In traveling through a heated tube, it is necessary to provide special means for an even annular distribution of the liquid upon the inner walls of the tube, and since most of these evaporators use a plurality of parallel tubes 30 heated by a common steam jacket and having a common feed, it is necessary to provide special means whereby the distribution of the liquid to the several tubes shall be made uniform, so that each such tube shall receive 35 substantially the same amount of liquid as every other tube.

In one of the modern types of evaporator known as the climbing film or "Kestner" type, the liquid is caused to travel upward as an 40 annular film through a heated tube or series of tubes, into a surmounting separating chamber wherein the evaporated liquid is separated from the vapor produced in evaporation. This chamber is usually under relatively low pressure, being connected with 45 means for removing vapor and for producing more or less of a vacuum therein. It is caused to travel upward in this manner by the presence of a central body or core of steam or 50 vapor passing upward in contact with it

and with considerable velocity. As actually manufactured, in this Kestner type of apparatus, there is a plurality of parallel vertical tubes surrounded by a common steam jacket. At their lower ends, these tubes pass through 55 a horizontal tube sheet into a feed chamber, the ends of the tubes depending into this feed chamber for some distance, say several inches. This chamber, although under greater pressure than that of the surmounting 60 separating chamber and being a pressure chamber relatively thereto, is usually under less pressure than the source of supply of the liquid. It operates under a pressure less than corresponds to the temperature 65 of the liquid supplied to it. Into this chamber is led liquid. This liquid when coming from a previous effect and therefore relatively hot, or when coming from a special preheater, on entering the feed chamber, 70 undergoes self-evaporation, some or much of its water flashing into vapor. The vapor and liquid pass upward through the heated tubes, the liquid traveling upon the inner wall of the tube as an annular layer, while 75 the vapor passes through the center of this annulus. In order to secure an even distribution of the liquid and vapor among the several tubes and to insure each tube securing the same relative amounts of liquid and 80 vapor, the depending ends of the tubes are provided with laterally presented orifices; the lower ends being slotted or beveled as the case may be. The hot liquid entering the feed chamber separates into vapor and 85 liquid, the vapor layer overlying the liquid layer. The laterally presented orifice at the base of the tube prolongations taps both the liquid and the vapor layers, insuring that some of each shall enter each tube. Without some such arrangement as this, the tubes are apt to receive liquid and vapor alternately, or some of the tubes may receive more liquid than others; some of the tubes may indeed be dry, taking nothing but vapor, while other tubes may be substantially or entirely filled with liquid. This is undesirable. It is, however, somewhat difficult to produce a uniform level of the liquid in 90 such a feed chamber as described. Since 95 100

the multiple effect is working under differential pressure and the entering liquid comes into the effect under relatively high pressure, it enters the feed chamber with considerable 5 velocity and tends to bank up more or less at one point or another within such chamber. It may, for instance, if the inlet be somewhat tangential, pass around to the opposite side of the chamber and there bank 10 up, giving a height of liquid higher than that next the inlet. Or the liquid may bank up near the inlet when coming in under less force.

In the present invention, I have devised a 15 process of and means for securing the desired even feed of both liquid and vapor to the several tubes and for insuring that each such tube shall receive the same relative amounts of liquid and vapor as each other 20 tube. For this purpose, I produce a preliminary separation of vapor and of liquid in a special preliminary chamber and then feed the vapor separated and the liquid separated individually into the feed chamber 25 proper of the apparatus. And in the modification of my invention at present preferred, I further introduce the steam or vapor into each tube as a positive jet, drawing in the liquid after it by what may be termed 30 an injector action. Where this is done, the prolongation of the tubes into portions depending into the feed chamber may be omitted, as may the laterally presented orifices. Where the separation of liquid and 35 vapor is effected in a preliminary chamber, it is, of course, practically immaterial whether the liquid banks up more at one point in such a chamber than at another, while the liquid separated may be fed uniformly 40 from such chamber into the feed chamber proper.

While this invention in some of its aspects is applicable to any type of evaporator wherein an annular traveling layer of 45 liquid is produced on the interior of a heated tube, in its present specific embodiment I regard it as more particularly applicable to evaporators of the stated "Kestner" or climbing film type.

50 In the accompanying showing, I have shown more or less diagrammatically certain organizations of apparatus elements within the limits of the present invention and useful in the performance of the stated process. In this showing: Figure 1, is a sectional elevation of one form of apparatus embodying my invention; Fig. 2, is a sectional plan view of the same; Fig. 3, is a view similar to Fig. 1, of a modified construction embodying my invention, and 55 Fig. 4, is a sectional plan view of the structure shown in Fig. 3.

In the operation of the elongated vertical tube evaporators of the said Kestner type 60 in which evaporation is effected by film

climbing of the liquid or liquid body under treatment, the essential result to be obtained is, as stated, the feeding of said liquid or liquid body to all of the tubes simultaneously and uniformly. The liquid coming 70 from a previous evaporator is superheated; that is, it is higher in temperature than the boiling point of the evaporator in which it is introduced, and the result is that the instant the liquid passes the feed valve, the 75 pressure being reduced, the boiling point is reduced also and some of the liquid flashes into steam, causing the liquid to be filled with bubbles.

In multiple effect evaporators, whether 80 working under vacuo or under pressure, the relative pressure in each succeeding effect is always lower than in the next preceding effect and, concomitantly, the boiling point of the liquid passing successively through 85 the several effects is also lowered so that the vapors from the preceding effect shall always be hot enough to boil the liquid in the next succeeding effect. The liquid in passing from one effect into the lower pressure of the next becomes partly vaporized and is full of bubbles of released steam. It is very desirable that these bubbles of steam should be separated and separately introduced into the tubes for ascent and 90 evaporation therein. One reason for this is that it is desirable to have a uniform liquid level near the ends of the tubes so that the feed in each tube will be uniform; the steam entering the tube independently 95 of the liquid, at the top of a laterally presented orifice or slot when such arrangement is provided, and the liquid entering the slot therebelow and passing up the tube adjacent the walls of the same. If this 100 level is not made uniform, or if there is a disturbance caused by the liquid entering at one side of the feed chamber, it will be readily understood that some of the tubes are apt to receive more liquid than others; 110 a condition that would interfere with the efficiency of the apparatus. Owing to the presence of the large amount of vapor, due to a fall in temperature and pressure when the liquid is passed from one effect to the 115 feed chamber of the next effect, there is always an opportunity for some of the tubes to receive a greater amount of liquid than others; and the essential object of my invention is to provide means whereby the 120 liquid and its accompanying vapor may be so controlled that the entrance of the same to the several tubes will take place simultaneously and with a substantially uniform body of liquid and vapor.

In the present embodiment of my invention, provision is made for definitely separating the liquid or liquid body from the steam or vapor which accompanies it prior to entering the feed chamber. To accom- 125

plish this, a separate chamber is provided disposed adjacent the feed chamber which is in direct communication with the tubes, and provision is made for independent transfer 5 of the liquid and the steam or vapor to said feed chamber and the tubes in communication therewith.

The forms of feeding device shown and described herein are designed to overcome 10 difficulties heretofore met with in feeding liquid or liquid bodies undergoing treatment to the base of evaporating tubes.

In Figs. 1 and 2, of the drawings herein, 1 represents the lower portion of a 15 heating shell or casing shown as of the "climbing film" type and containing evaporating tubes 2 to which the liquid or liquid body to be concentrated is to be fed for ascent therein. Carried by the shell or casing 20 1 is a tube sheet 3 to which the tubes are connected, while in the structure shown in Figs. 3 and 4, the tubes pass through said tube sheet into a feed chamber 4, and in such instance the tubes may be beveled or 25 provided with laterally presented orifices or slots 5, in the manner indicated in my prior Patent No. 882,322.

Referring again to Figs. 1 and 2, 7 represents a chamber disposed adjacent the casing 1, and into which the heated liquid to 30 be concentrated is fed from a suitable inlet 8, and in which chamber more or less perfect separation of the steam or vapor from the liquid may be effected; such steam or 35 vapor being passed directly to the evaporating tubes 2. For this purpose the chamber 7 has a passage 9 for delivering the liquid to the chamber 4 below the tubes and in direct communication therewith, and a passage 10 with an inlet conduit 11 at the top of the chamber 7, which passage communicates with a chamber 12 below said chamber 4, and from this chamber 12 the steam or 40 vapor may enter the evaporating tubes 2 through short sections of tubing indicated at 13. In this form of the structure, no provision is made for extending the tubes 2 into the feed chamber, but such arrangement is not thought to be necessary with 45 this particular structure in view of the direct means used for transferring the steam or vapor to the evaporating tubes.

In the structures shown in Figs. 3 and 4, the liquid enters an auxiliary chamber 7^a 55 and flows via a passage 14 to the feed chamber 4 into which the evaporating tubes 2 project and strike a deflector or baffle 15 therein which serves to spread the liquid to all parts of said chamber. The steam or 60 vapor accompanying the liquid or developed within said chamber 7^a rises to the top of the same and enters the feed chamber 4 via a passage 16 which leads from a point near the top of said chamber 7^a and 65 circulates around the upper portion of the

feed chamber 4 simultaneously with the entry of the liquid therebelow and with the latter wetting the inner walls of the tubes 2 uniformly and simultaneously; it facilitates the flow of liquid therein, and the operation 70 in the subsequent concentration of the same. With the projecting tubes, the laterally presented orifices 5 will tap both steam and liquid layers, allowing a simultaneous entry of both into each tube, but with the structure of Fig. 1, positive means are provided for the delivery of liquid and of vapor into each evaporating tube and the beveling or slotting of the tube ends and their prolongation becomes unnecessary. 80

The structures shown herein as auxiliary to the evaporator may be of sheet metal or cast metal, or parts may be of sheet metal and parts of cast metal. The tubes 2 may be projected into the feed chamber 4 as indicated in the structure shown in Figs. 3 and 4, to any desired extent; the desirability of such extension depending in some measure upon the size and capacity of the evaporating element. The several feed chambers 90 are provided with suitable drainage outlets 18 closed by plugs—or other suitable devices, or they may be provided with valves 20. In addition, the feed chamber in each instance is so constructed and arranged and 95 of such size with respect to the shell containing the evaporating tubes that all of said tubes are accessible when said feed chamber or the lower portion of the same is removed. 100

The feature of the present invention is the provision of auxiliary means exterior of the main feed chamber and in communication with the evaporating tubes for the separation of the steam or vapor from the liquid, and the separate feeding of said steam or 105 vapor and of said liquid to the tubes.

An evaporator with the auxiliary devices shown comprising means for effecting an even feed and distribution of the liquid 110 may be used as a single evaporating effect or as any effect of a multiple effect system and it may be operated under a pressure greater or less than that of the atmosphere. Any number of similar effects of this type 115 may be arranged in a multiple effect system or one such effect may be arranged in combination with effects of a different type. It should, however, in whatever arrangement it be used, be so arranged as to receive a supply of liquid of a heat greater than the boiling point at the pressure prevailing in the effect so as to permit self evaporation to take place in the preliminary chamber. When used as a single effect or as 120 the first effect of a multiple, it should therefore be coupled with a source of preheated liquid. 125

I claim:

1. In an evaporating apparatus, an evap- 130

orating tube, a heating casing surrounding such tube, a source of heated liquid, an expansion chamber receiving such heated liquid, a vapor conduit leading from such chamber and in communication with such tube, and a liquid conduit leading from such chamber and also in communication with such tube.

2. In an evaporating apparatus, a vertical evaporating tube, a heating casing surrounding such tube, a source of heated liquid, an expansion chamber receiving such heated liquid, a vapor conduit leading from such chamber and in communication with such tube, and a liquid conduit leading from such chamber and also in communication with such tube.

3. In an evaporating apparatus, an evaporating tube, a heating casing surrounding such tube, a source of heated liquid, an expansion chamber receiving such heated liquid, a vapor conduit leading from such chamber and having a prolongation extending some distance within the end of such evaporating tube, and a liquid conduit leading from such chamber and also in communication with such tube.

4. In an evaporating apparatus, a vertical evaporating tube, a heating casing surrounding such tube, a source of heated liquid, an expansion chamber receiving such heated liquid, a vapor conduit leading from such chamber and having a prolongation extending some distance within the end of such evaporating tube, and a liquid conduit leading from such chamber and also in communication with such tube.

5. In a tubular evaporator, the combination of a feed chamber at the base of the tubes for receiving heated liquid under treatment, evaporating tubes leading upwardly from said chamber, a chamber situated independently of said feed chamber for initial reception of the liquid to permit separation of vapor therefrom, and means for the separate delivery of liquid and vapor to the evaporating tubes.

6. In an evaporating apparatus, the combination of vertical tubes, a feed chamber communicating with the lower ends of the same, a chamber for the reception of heated liquid undergoing treatment in which accompanying vapor may separate from such liquid, and means for separately passing vapor and liquid to the evaporating tubes.

7. In an evaporating apparatus, the combination of vertical tubes, a chamber communicating with the lower ends of the same, a chamber for the initial reception of heated liquid undergoing treatment in which accompanying vapor may separate from such liquid, a plurality of chambers below the lower ends of the tubes, one of which communicates directly with said tubes, and separate passages for vapor and liquid leading

from the separating chamber to the chambers below the ends of the tubes, one of said chambers having vapor outlets communicating with the evaporating tubes.

8. The combination of an evaporator having vertical heating tubes in an inclosing casing, means at the base of said casing for feeding liquid and vapor into said tubes, a releasing casing having an inlet for liquid to be treated, a conduit establishing communication between the upper part of said releasing casing and said feed means; and another conduit establishing communication between the lower part of said releasing casing and said feed means.

9. The combination of an evaporator having vertical heating tubes in an inclosing casing, means at the base of said casing for feeding liquid and vapor into said tubes, a releasing casing having an inlet for liquid to be treated, a conduit establishing communication between the upper part of said releasing casing and said feed means, said conduit having an extension within the base of each evaporating tube, and another conduit establishing communication between the lower part of said releasing casing and said feed means.

10. The combination of an evaporator, means for evaporating liquid as a climbing film, feeding means, a source of heated liquid, means for permitting a release of vapor from such liquid, and means for separately conducting the released vapor and the residual liquid to said feeding means.

11. An evaporating element having a pressure chamber and vertical tubes extending into said chamber, in combination with means for separating vapor from liquid and delivering it to said pressure chamber above the inlets to said tubes, and means for conveying liquid from which said vapor is separated to said pressure chamber below the inlets to said tubes.

12. The combination of a vertical tube evaporator, means for relieving the pressure on a body of heated liquid to form separate bodies of vapor and liquid, means for delivering the residual liquid to the lower ends of the tubes and means for delivering vapor to the tubes to facilitate the passage of the liquid into and through the same.

13. The combination of a vertical tube evaporator, means for causing self evaporation in a body of liquid to be treated, means for delivering the residual hot liquid to the bottoms of the evaporator tubes and means for supplying a jet of vapor to the bottoms of the tubes to facilitate the flow of said liquid into and through the same.

14. The combination of a vertical tube evaporator having a feed chamber at the lower ends of the tubes, a container for relieving the pressure on a body of liquid to be treated to permit self evaporation thereof, a

conduit for delivering the residual liquid from said container to the feed chamber, and means independent of said conduit for delivering vapor to the feed chamber to facilitate the passage of the liquid into and through the tubes.

5 In testimony whereof, I have signed my

name to this specification, in the presence of two subscribing witnesses.

PAUL KESTNER.
